(57) **CLAIM**

The ornamental design for a clip for a head attachment system, as shown and described.

DESCRIPTION

FIG. 1 is a perspective view of an embodiment of a clip for a head attachment system;

FIG. 2 is a front view of the embodiment of FIG. 1;

FIG. 3 is a rear view of the embodiment of FIG. 1, which is mirror image of FIG. 2;

FIG. 4 is a top view of the embodiment of FIG. 1, while FIG.

5 is a bottom view of the embodiment of FIG. 1;

FIGS. 6–7 are side views of the embodiment of FIG. 1, which are mirror images;

FIG. 8 is a reference view showing use of the embodiment of FIG. 1 with an optional exemplary mask strap; and,

FIG. 9 is a second reference view showing use of the embodiment of FIG. 1 with an optional exemplary mask.

Any broken lines show in the drawings are only provided to illustrate the environment of the design, and form no part of the claimed design. In instances where an opposite side of an embodiment is not specifically illustrated and might not be fully apparent from the presented side figure(s) in conjunction with the presented perspective figure, such opposite side may be a mirror image of the side which is specifically illustrated.
